No. 673,467.

Patented May 7, 1901.

L. BOCHE.
CANDLE HOLDER.

(Application filed July 30, 1900.)

(No Model.)

UNITED STATES PATENT OFFICE.

LOUIS BOCHE, OF CHICAGO, ILLINOIS.

CANDLE-HOLDER.

SPECIFICATION forming part of Letters Patent No. 673,467, dated May 7, 1901.

Application filed July 30, 1900. Serial No. 25,329. (No model.)

To all whom it may concern:

Be it known that I, LOUIS BOCHE, a citizen of the United States, residing at Chicago, in the county of Cook and State of Illinois, have 5 invented certain new and useful Improvements in Candle-Holders; and I do hereby declare the following to be a full, clear, and exact description of the invention, such as will enable others skilled in the art to which 10 it appertains to make and use the same.

This invention relates to improvements in candle-holders of the kind adapted to be used on Christmas trees in lighting the same.

The invention consists, substantially, in the 15 novel method of securing the candle to the holder and of attaching the same to the branches of the tree, as will be hereinafter fully described and set forth, reference being had to the accompanying drawings, in which—

20 Figure 1 is a miniature representation of a Christmas tree, to the branches of which the holder is adapted to be attached. Fig. 2 is an elevation of the complete holder with a candle inserted, the holder being shown of normal size and the socket-body a section 25 taken on the line 2 2 of Fig. 5; Fig. 3, a like view, with the largest or standard size of candle set in the uppermost part of the holder; Fig. 4, a transverse section taken on the line 30 4 4 of Fig. 3, showing the inner longitudinal ribs, the edges of which are adapted to secure the candle to the holder. Fig. 5 is a plan view of the socket-body and drip-cup, and Figs. 6, 7, and 8 are designed to illustrate the 35 peculiar mode of attaching the holder to the tree-branches.

Referring to the drawings, 1 designates the socket-body of the holder, which, as will be seen, is formed to taper from near the top 40 conically downward to the bottom, the upper part of the socket being curved outward to form a cup for the candle-drippings. Said socket-body is provided with inner longitudinal ribs 2, which project radially therefrom.

45 Said ribs are formed thin, with sharp edges adapted to penetrate the candle 3 when inserted between them and to hold it firmly in position, and by reason of their being conically formed, wider apart at the top, said 50 socket-ribs are adapted to receive and hold

the various sizes of candles manufactured for the purpose. Said socket-body is also provided at the top with a secondary set of projecting ribs 4, made shorter than the first described, and are wider apart, being adapted 55 only for the largest or standard make of candle 5, as shown in Fig. 3. Said socket-body, ribs, and drip-cup are adapted to be formed integral from any suitable material, as tin, glass, or iron, either by stamping or casting, 60 as may be found most desirable.

6 is a wire or rod the upper end portion of which is rigidly secured to the bottom of the socket-body, the lower end of said wire being provided with a counterbalance-weight 7, by 65 means of which the holder is held in an upright position when attached to a branch 8 of the tree. Said wire has a free end portion 9, which extends a distance down from the socket, and which, together with a portion of 70 the body-wire, is relatively bent and twisted spirally to form a loop 10 at the bottom of the socket-body. Said wires are in contact at a point a, Fig. 2, and from thence are still further spirally bent until the extremity of 75 the free end portion and body of the wire stand apart, forming a gap N, Fig. 6, into which the branch of the tree is inserted and which in its course to the final point at the base of the socket springs the wires apart at 80 the contact-point and which close together thereafter, inclosing the branch in a continuous spiral loop, the action being in effect a screwing of the holder on the branch of the tree, the holder making about a half-turn in 85 the process, as will be understood from an inspection of the drawings, the arrangement being such that the holder cannot be easily thrown from the tree and is convenient of attachment thereto.

90 Having described my invention, I claim—

1. The combination in a candle-holder of a candle-socket, a wire rod rigidly secured to the lower end of said socket, said wire rod formed with two downwardly-projecting arms 95 or end portions of unequal lengths, the longer one of said arms provided with a counterpoise-weight, and the shorter or free arm adapted to form a spiral loop or opening between portions of the two arms, said spiral 100

opening adapted for the insertion of the branch of a tree or other support substantially as set forth.

2. The combination in a candle-holder of a socket provided with internal ribs, a wire rod rigidly secured to said socket, said wire bent and formed to cause said candle-holder to turn or rotate upon its axis when being attached to or taken from a tree or support, and a counterpoise-weight secured to said

wire and adapted to keep said candle-holder in an upright position, substantially as set forth.

In testimony whereof I affix my signature in presence of two witnesses.

LOUIS BOCHE.

Witnesses:

HENRY ROTH,
L. SCHWAL.
